ELECTRICAL MUSICAL INSTRUMENT

Pierre P. Pattyn, Detroit, Mich., assignor, by
mesne assignments, to John A. Patroske

Application June 15, 1949, Serial No. 99,234

2 Claims. (Cl. 84—1.28)

1

This invention relates to an improved electrical musical instrument.

An object of this invention is to provide an electrical musical instrument with means for voicing and combining tones and which gives the performer powers of expression which are far greater than those possessed by any other instrument.

Another object of this invention is to provide an instrument incapable of getting "out of tune" so long as the speed of the driving motors remain constant.

A further object of this invention is to provide an improved electrical musical instrument which is capable of producing a plurality of musical sounds.

A further object of this invention is the provision of an apparatus for selectively reproducing instrumental compositions and in variable volume.

A further object of this invention is the provision of an apparatus for selectively reproducing instrumental compositions high enough in volume for the rendition of musical compositions in large auditoriums and low enough in volume for practice purposes.

A further object of this invention is to provide a musical instrument capable of producing an unlimited variety of musical tones.

A further object of this invention is to provide a musical instrument whereby new and interesting musical results may be obtained.

Another important object of the invention is to provide means whereby the tones of a number of different sounds, may be produced simultaneously; also to provide a means for quickly changing from one combination of tones to another combination of tones.

It is an important object of the invention to provide means for producing musical tones or any other sounds without accompanying mechanical or electrical noises due to operation of the mechanism constituting the invention.

A further object of the invention is the provision of means whereby a given note or combinations of notes or sounds may be sustained for any length of time.

A further object of this invention is to provide an instrument for reproducing and simulating musical notes and instruments wherein all rotatable members have a record of fundamentals, harmonics and overtones which can be selectively controlled by the operator.

With the additional purpose of providing a mechanism of the character stated which is

2

simple in construction, relatively cheap and easy to produce, which may be compactly assembled and which is thoroughly reliable and efficient in use, and with various other purposes in view, the invention consists of novel features of construction, combinations and arrangements of parts as will be hereinafter more fully described, illustrated in the accompanying drawings and defined in the appended claims.

10 In the drawings,

Figure 1 is a detail side elevation, partly broken away and in section, of an electronic musical instrument constructed according to an embodiment of this invention.

15 Figure 2 is a rear elevation, partly broken away, of the instrument,

Figure 3 is a fragmentary vertical section of the instrument,

20 Figure 4 is a diagrammatic view showing the electric circuits embodied in this invention,

Figure 5 is a fragmentary sectional view taken on the line 5—5 of Figure 1,

25 Figure 6 is a fragmentary longitudinal section of one of the note or tone reproducing units.

25 Referring to the drawings, the numeral 10 designates generally a cabinet which is formed of opposite side walls 11, a top wall 12, and a front wall 13. The cabinet 10 is provided with a plurality of horizontally disposed shelves 14 which are vertically spaced apart so as to provide unit chambers 15, the purpose for which will be hereinafter described.

The cabinet 10 also includes a keyboard 16 having a plurality of keys or levers 17 rockably mounted on mountings 18. Each compartment or chamber 15 has mounted therein a plurality of instrumental note unit members generally designated as 19, which are disposed in sidewise abutting relation. Each unit 19 includes a housing or case 20 which has mounted therein an electro-magnetic pickup member 21 carried by a standard or mounting 22.

45 An endless web or tape 23 engages over the pickup member 21 and also engages about a pair of grooved rollers 24 and 25. The roller 25 is rotatably carried by a vertically disposed rock lever 26 mounted on a supporting 27 carried by the base 28 of the case 20. The lever 26 extends above the roller 25 and terminates in an armature 29 disposed in confronting position to an electro-magnetic operator 30 which is disposed in a housing or case 20. The lever 26 is limited in its rocking in a counter-clockwise direction by means of a stop 31 which is carried by the housing 20.

The web or tape 23 which is formed of fibrous material such as paper or the like, and has embedded therein metal particles adapted to be magnetized, is kept substantially taut by means of a gravity roller 32 which is carried by a lever 33, and the lever 33 is rockably carried by a standard or upstanding support 34 which is secured to the base 23.

The electro-magnetic pickup member 21 includes a male contact member 35, as shown in Figure 5, which extends through one side wall 36 of the housing 20, and also includes a female contact member 37 extending through the opposite side wall 38 of the housing 20. In this manner the electro-magnetic pickup members 21 are connected in series and the endmost units are connected to an audio amplifying unit 39 by means of conductors 40 and 41. A volume control member 42 is interposed in conductor 41, and as shown in Figure 4, the output side of the amplifier 39 is connected to a loud speaker 43.

The side walls 36 and 38 of the housing 20 are provided with horizontally extending slots 44 within which a driving shaft 45 connected to and operated by a motor 46 is adapted to engage. The wheel or roller 25 has fixed relative thereto a friction wheel 47 which upon clockwise rocking of lever 28 is adapted to frictionally engage the drive shaft 45 to thereby move tape 23 over the stationary pickup member 21. The pickup members 21 are in constant circuit with the amplifier 39 and when the electro-magnetic member 30 is energized, lever 28 will be rocked clockwise to engage driving wheel 47 with shaft 45 so that selected ones or groups of tapes 23 will be moved with respect to the electro-magnetic pickup member 21.

The electro-magnetic members 30 are connected by means of a conductor 50 to one side of an electric supply source, and as shown in Figure 4, the motor 46 for each group of unit members 19 is connected across a supply wire 51 and a conductor 52 which connects electro-magnetic member 30 with a key operated switch structure generally designated as 53. The switch 53 includes a common contact carrying bar 54 which is secured to a support 55 disposed above the keyboard member 16, and contact carrying bar 54 is connected to conductor 51.

Switch 53 includes an adjustable contact member 56 and a resilient contact 57 disposed in confronting position to contact 56. Contact 57 is connected to conductor 52 and contact 57 extends forwardly in a position to overlie the inner or rear end of a key or lever 17. Each key or lever 17 is biased upwardly at its forward end by means of a flat spring 58, and a cushion or felt 59 is disposed adjacent the rear of key 17 and is mounted on a block 60. A second cushion or felt 61 is mounted on the board 16 adjacent the forward end of key 17 so that the forward end of the key 17 will strike cushion 61 when key 17 is depressed at its forward end to a switch closing position.

In the use and operation of this instrument, each compartment 15 will have mounted therein a plurality of units 19 comprising essentially the complete scale of notes for a particular instrument. As an example, the uppermost compartment may have notes recorded from an organ, the succeeding compartment having units bearing notes from a piano and the other compartments may have other instrumental notes such as brass, string or percussion instruments. The volume control member 42 with its associated

switch 48 is mounted on a panel board 62 which is disposed above the keys 17, as shown in Figure 3. When, as an example, it is desired to play the notes from an organ, the control member and switch 42-48 connected with the organ units is turned on whereupon the keys 17 may be played in the normal manner. As each key 17 is depressed, the associated electro-magnetic member 30 will be energized, thereby setting into operation the associated tape 23. At the time the combined control member and switch 42-48 is turned on, the correlated motor 46 is energized and shaft 45 will be continuously rotated so that the selected tapes 23 will be moved when the associated electro-magnet members 30 are energized. It will, of course, be understood that with an instrument as hereinbefore described, one or more series of reproducing units may be combined, it only being necessary to turn on the combined control and the switch unit 42-48 for the particular series of note units of the selected instruments. In this manner the playing of the keys 17 will effect a reproduction of notes and tones from either one or a series of instruments at the same time, thereby producing the effect of an orchestra or symphony through the single instrument.

As shown in Figure 1, the loud speaker 43 may be disposed at the forward portion of the cabinet 10 beneath the keyboard and the audio amplifier 39 may be positioned in a bench or seat 64 on which the operator is seated. By providing the units 19 as hereinbefore described with the pickup members 21 connected in series, it is a relatively simple matter to replace any unit 19 and a very considerable reduction in wiring is effected. Furthermore, by providing for the starting and stopping of the tape movement through the electro-magnetic member 30, it is possible to produce what is termed the "live" characteristics of musical notes, thereby eliminating the synthetic note reproduction obtained from oscillating tubes and circuits.

It will be understood that the "live" characteristics of a note are defined as an initial retarding of the tone note and a similar final retarding of the note which normally occurs when the note is produced manually on a musical instrument. While this initial and final tapering of the note tone is infinitesimal, it is nevertheless a characteristic of manually produced notes which have not heretofore been capable of reproduction in mechanical instruments.

I do not mean to confine myself to the exact details of construction herein disclosed, but claim all variations falling within the purview of the appended claims.

What I claim is:

1. A musical instrument comprising a plurality of keys, a plurality of electro-magnetic note units disposed in side by side relation, each unit comprising a housing formed with a rearwardly opening slot, a flexible normally stationary endless sound reproducing element in said housing, a driving wheel for said element in said housing and projecting rearwardly into said slots, a common operator for said driving wheels projecting into said slots, a power circuit for said operator, an amplifying unit, electric circuits coupling said note units with said amplifying unit, a plurality of electromagnetic circuits, electro-magnetic means in said latter circuits for coupling said driving wheels with said operator, a plurality of key-operated switches interposed in said electro-

magnetic circuits, and a loud speaker connected to the output of said amplifying unit.

2. In a musical instrument, a plurality of electro-magnetic note units disposed in side-by-side relation, each unit including a flexible normally 5 stationary endless magnetized member, a common operator for said members, a power circuit for said operator, a plurality of sound impulse transmitting electric circuits, a plurality of electro-magnetic pickup members disposed in co- 10 operative relation with respect to said endless members and interposed in said latter circuits, electro-magnetic means for coupling each unit with said operator, electric circuits for said electro-magnetic means, and key-operated switches 15 interposed in said latter circuits.

PIERRE P. PATTYN.
